UNITED STATES PATENT OFFICE.

WILLIAM H. BAKER, OF CENTRAL FALLS, RHODE ISLAND, AND FREDERIC E. KIP, OF MONTCLAIR, NEW JERSEY.

LOOM.

SPECIFICATION forming part of Letters Patent No. 656,613, dated August 21, 1900.

Application filed April 27, 1900. Serial No. 14,544. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Looms, of which the following is a specification.

10 This invention relates to double-shuttle looms, and has for its object to provide means for supplying weft to the shuttles or weft-carriers of the loom as required through mechanism automatically controlled by exhaustion-indicating devices made inoperative and operative, respectively, by the presence or absence of weft or filling in the active shuttles.

15 In the accompanying drawings, which illustrate an embodiment of the invention, Figure 1 is a side elevation, on a relatively-small scale, of a loom provided with our improvements; and Fig. 2 is a front elevation of the lay, showing the shuttle-boxes and picking mechanism. Fig. 3 is a sectional side view on a larger scale, showing the construction more in detail; and Fig. 4 is a sectional front view on the same scale as Fig. 3, showing the magazine in vertical axial section. Fig. 5 is 20 a view of the detent device detached. Fig. 25 6 is a detail view of the shuttle-box and shuttle therein as seen from the front. This view shows the electrical connections. Fig. 7 is a 30 sectional view of the shuttle and of the bobbin or weft-holder therein. Fig. 8 is an enlarged view of the detachable spindle for the 35 weft-holder.

a is the loom-frame, and *b* the breast-beam, forming a portion thereof.

40 *c* is the lay, and *d* the lay-swords.

e and *e'* are the upper and lower shuttle-boxes on the lay.

45 On a horizontally-arranged spindle *f*, fixed in a bracket *g* on the loom-frame, is rotatively mounted a drum-like magazine *M* to carry the weft to be supplied to the shuttles *h* in the boxes on the lay. This magazine consists of a head or end *i*, a sleeve-like boss *j*, and bars *k*, extending from said head par-

50 allel with the axis or boss, where they are connected by a ring *l*, thus leaving the inner end of the magazine open. The bobbins *m* are held in place by suitable spring-clips *n*, so that the bobbins may be easily displaced laterally by drivers *o* and *o'*, which drive them into the shuttles in the respective boxes *e* and *e'*, displacing therefrom the empty bobbins. The magazine is rotated through a belt *p*, which is driven from a sheave *q* on a shaft *r* of the loom and takes over a sheave *s*, 55 rotatively mounted on the boss *j* of the magazine. This sheave contains a spring *t*, one end of which is secured to the pulley and the other to the boss *j*. The magazine is held against rotation by a detent device, to be 60 hereinafter described, and when the spring *t* is wound up the belt *p* slips on the sheave *s*. Therefore when the magazine is released it is 65 instantly rotated by the spring *t*.

The detent device is best seen in Figs. 3 70 and 5. It comprises two like rocking detents *u* and *u'*, carried on an arm *v*, which projects from the bracket *g*. Each detent rocks on a stud *w*, projecting out laterally from the arm *v* and they are coupled together by a link *x*, the link taking hold of the upper detent *u* back of the pivot and of the lower detent *u'* in front of the pivot, so that when one detent rocks the other detent in the opposite direction. To prevent the detents from 75 rocking too far in either direction, a stud *y*, extending from the bracket-arm, engages a limiting-slot in the link *x*. The detents *u* and *u'* take over the respective upper and lower bobbins *m*, presented at the delivery- 80 point in front of the drivers *o o'* and prevent the rotation of the magazine (in the direction of the arrow *z* in Fig. 3) so long as both bobbins are in place. If the upper bobbin be driven into the shuttle, the magazine will turn until 85 the lower bobbin takes the place left vacant, the next bobbin below rising to take the lower position; but if the lower bobbin be displaced the magazine will rotate until the bobbin next below it takes the upper position—that is, when the lower bobbin is displaced the magazine rotates to the extent of two bobbins.

The drivers *o o'* are fulcrumed at 1 on the loom-frame and have laterally-projecting 90

95 50 bars *l*, extending from said head par-

heads which extend into the open inner end of the magazine, and each driver carries pivoted to it below said fulcrum an arm 2, which may by lowering it be put into the path of a 5 tappet 3, carried by the lay. As herein shown, this tappet is fixed to one of the lay-swords and is broad enough to actuate either of the arms 2, which may be put into its path. The respective arms 2 are supported on arms 10 mature-levers 4 and 4', carrying the armatures 5 and 5' of two electromagnets 6 and 6', and when either magnet attracts its armature the corresponding arm 2 is lowered into the path of the tappet 3, whereby when the lay 15 beats up the driver to which said arm is attached drives the bobbin *m* in front of it at the delivery-point out laterally from the magazine into the shuttle, expelling at the same time the exhausted bobbin from the 20 shuttle in the box. The magnets 6 and 6' are in electric circuits 7, one of which is seen in Fig. 6, and the operation of the respective drivers is controlled by the presence or absence of weft in the respective shuttles in 25 play. Referring to Figs. 6 and 7, the electrical construction will be described, promising that as each shuttle and shuttle-box is fitted up electrically in the same way a description of one box and shuttle will serve for 30 both.

The shuttle *n* has clips or spring-jaws 8 to keep the weft holder or supporter *m* in place. This is a known device; but in this instance the clips are arranged above and below and 35 not at the sides of the device which holds the weft. This device comprises a laterally-compressible metal spindle 9, detachable from the shuttle, and best seen in Fig. 8. This spindle is provided with a headpiece 10, which 40 may be of wood, and about the latter are two metal bands or rings 11, which are embraced by the jaws 8. These latter hold the spindle firmly but detachably in the shuttle. The butt or end of the metal spindle is in electrical 45 contact with a metal plate 12 on the shuttle, and the plate 12 is electrically connected by a suitable conductor 18 with a metal contact-plate 13 on the face of the shuttle at that end, while the jaws 8 are connected electrically by a suitable conductor 19 with a metal contact-plate 13' at the other end of the 50 shuttle. Thus the head of the spindle 9 is in electrical connection with the plate 13 and the rings 11 are in similar connection with the plate 13'. Fixed in electrical contact with the end of the spindle is a contact-spring 14, which forms the indicator and plays in a slot in the block 10 and tends normally to spring outward into electrical contact with one or 55 both of the rings 11, thus closing the circuit between the plates 13 and 13'. The actual holder of the weft is a butt-cop 15, which may be slipped on the spindle 9. This butt-cop (or it may be a full bobbin) has a groove into 60 which the free end of the spring 14 enters when the cop is slipped onto the spindle. Now if the cop or bobbin carries weft 16, as

seen in Fig. 6, the spring-indicator 14 passes under the weft and is pressed inward, so as to break the contact between said indicator and the ring or rings 11; but when the weft becomes substantially exhausted the spring-indicator will again close the circuit by forming contact with the rings. Now when the shuttle enters its box the plates 13 and 13' 70 will be put into contact, respectively, with spring-terminals 17 and 17' of the circuit, as seen in Fig. 6, thus completing the circuit through the electromagnet 6 or 6' belonging to this particular shuttle-box. 75

In Fig. 6, 20 designates any suitable generator to supply the circuit 20'. Of course by employing suitably-arranged conductors one generator may serve for energizing both magnets. This will be understood by any 80 electrician.

The construction of the drivers *o* and *o'*, the magnets, and the operating-tappet is substantially the same as those shown in our pending application, Serial No. 9,493, filed 90 March 21, 1900, and is not specifically claimed herein.

The particular construction of the contact devices in the shuttle and bobbin is not material to our invention so long as it is controlled by the presence or absence of weft 95 therein. The contact-spring 17, held out of contact manually at the break by the over-wrapped weft, may be as illustrated in our United States Patent No. 637,195, dated November 14, 1899.

The pickers 21 and the picker-stick 22 (seen in Figs. 1 and 2) possess no special or novel features, and indeed any kind of picker devices suited to the purpose may be employed. The lay may be vibrated by means of cranks in the shaft *r* and connecting-rods *r'* in a known manner.

In Fig. 4 the weft-end holder 23 is indicated, but is represented for lack of room as partly 110 broken away. There is nothing novel in this feature.

The novel feature of automatically supplying from a rotatable creel, feeder, drum, or magazine when required at the same time or 115 on the same pick of the loom both the upper and lower shuttle or either the upper or the lower shuttle of a double-shuttle loom, with a bobbin or weft-holder containing weft or filling to replace that substantially exhausted, 120 the said mechanism being so constructed that when the upper shuttle has been supplied the magazine will automatically rotate, so that it moves up to the extent of only one bobbin or weft-holder and then stops, but when the 125 lower shuttle has been supplied or when both the upper and lower shuttles happen to be supplied on the same pick of the loom the magazine will automatically rotate, so that it moves up to the extent of two bobbins or 130 weft-holders and then stops, is of course equally-well adapted to a mechanically-controlled weft-supply as an electrically-controlled weft-supply—as, for example, the me-

chanically-controlled weft-supply illustrated in our pending application, Serial No. 15,786, filed May 7, 1900.

By "weft-holder," as herein expressed, is meant any receptacle holding weft or filling—such as a weft or bobbin case containing weft or filling, or bobbin, butt-cop, cop, and the like containing weft or filling. The magazine herein illustrated is also adaptable to carry any known form of weft-holder.

By "absence" or "substantial absence" and "exhaustion" or "substantial exhaustion" of weft or filling from the shuttles in play, as herein expressed, is not necessarily meant the entire absence of the weft or filling, but such degree of exhaustion as will allow the exhaustion-indicating device to perform its function.

The spindle 9 is split and laterally compressible, as in the common form of spindle used in shuttles.

Having thus described our invention, we claim—

1. In a loom, the combination with two superposed shuttle-boxes, and shuttles, both adapted to receive and discharge weft-holders laterally, and means for picking the shuttles from said boxes simultaneously, of a magazine comprising a rotatable carrier provided with means for supporting weft-holders concentrically arranged about the axis of the carrier, means for moving said carrier, a detent for holding said carrier against movement normally with weft-holders opposite the superposed shuttle-boxes, two drivers for driving the weft-holders from the carrier into the respective boxes, means for actuating said drivers at proper times, and means controlled by the presence or absence of weft or filling in the respective shuttles for setting said drivers in operation.

2. In a loom, the combination with two superposed shuttle-boxes, and shuttles, both adapted to receive and discharge weft-holders laterally, and means for picking the shuttles from said boxes simultaneously, of a magazine comprising a rotatable carrier provided with means for supporting weft-holders concentrically arranged about the axis of the carrier, means for moving said carrier, a detent for holding said carrier against movement normally with weft-holders opposite the superposed shuttle-boxes, two drivers for driving the weft-holders from the carrier into the respective boxes, means for actuating said drivers at proper times, and electro-magnetic means controlled by the presence or absence of weft or filling in the respective shuttles for setting said drivers in operation.

3. In a double-shuttle loom, the combination with means for picking the shuttles through two warp-sheds, a movable magazine or feeder, for weft-holders, having devices for supporting a plurality of weft-holders arranged concentrically about the axis of the magazine, means for transferring as required either one or two weft-holders at the same

time, from the said magazine to either or both of the shuttles in play, the time of operation of said supplying mechanism being controlled by the presence or absence of weft or filling in the shuttles in play.

4. In a double-shuttle loom, the combination with means for picking the shuttle through two warp-sheds, a movable magazine or feeder for weft-holders, having devices for supporting a plurality of weft-holders arranged concentrically about the axis of the magazine, means for transferring, as required, one or two weft-holders at the same time from the said magazine, to either or both of the shuttles in play, means for controlling the times of operation thereof, said means consisting of an electric circuit connected with said supplying mechanism and made inoperative and operative, respectively, by the presence or substantial absence of weft or filling in the shuttles in play.

5. In a loom, the combination of two superposed shuttle-boxes, of means for picking two shuttles through two warp-sheds about the same time, a rotatable magazine, having means for carrying bobbins or weft-holders concentrically arranged about the axis of the magazine, means for supplying from said magazine to either or both of said shuttles, a weft-holder containing a supply of weft or filling in place of that substantially exhausted, the times of operation of said supplying mechanism being controlled by the presence or substantial absence of weft or filling in the shuttles in play.

6. In a loom, the combination of two superposed shuttle-boxes, of means for picking two shuttles through two warp-sheds at about the same time, a rotatable magazine, having means for carrying bobbins or weft-holders concentrically arranged about the axis of the magazine, means for supplying from said magazine to either or both of said shuttles, a weft-holder containing a supply of weft or filling in place of that substantially exhausted, and means for controlling the times of operation thereof, said means consisting of an electric circuit connected with said supplying mechanism and made inoperative or operative, respectively, by the presence or substantial absence of weft or filling in the shuttles in play.

7. In a weft-supplying mechanism, the combination with means for picking shuttles through two warp-sheds, at about the same time, a rotatable feeder or magazine adapted to carry reserve supply of weft-holders concentrically arranged about the axis of the magazine, two drivers adapted to drive or push, as required, either or both of the weft-holders at the delivery-point into their respective shuttles during the same pick of the loom, and means connected with said feeder or magazine for always presenting to the proper delivery position two weft-holders, independent of whether one or both of said weft-holders have been previously trans-

ferred from said magazine to the shuttles, the time of operation thereof being controlled by the presence or substantial absence of weft or filling in the shuttles in play.

5 8. In a weft-supplying mechanism, the combination with means for picking shuttles through two warp-sheds at about the same time, a rotatable feeder or magazine adapted to carry reserve supply of weft-holders concentrically arranged about the axis of the magazine, two drivers adapted to drive or push as required, either or both of the weft-holders at the delivery-point into their respective shuttles during the same pick of the 15 loom, means connected with said feeder or magazine for always presenting to the proper delivery position both weft-holders, independent of whether one or two of said weft-holders have been previously transferred 20 from said magazine to the shuttles, and means for controlling the times of operation of the supplying mechanism, said means consisting of an electric circuit connected with said supplying mechanism and made inoperative by 25 the presence, and operative by the substantial absence, of weft or filling in the shuttles in play.

9. In a weft or filling supplying mechanism for looms, the combination with means for 30 traversing two shuttles, through two warp-sheds at each pick of the loom, a rotatable feeder or magazine containing a reserve supply of weft or filling in the form of concentrically-arranged weft-holders, means for rotating said magazine, a restraining device preventing, periodically, said rotation, said restraining device being made operative when two of the said weft-holders engage it, and inoperative on either one or both of said weft-holders being removed from said engagement, 40 and means for transferring the weft-holders at the delivery-point to their respective shuttles, substantially as set forth.

10. In a weft or filling supplying mechanism for looms, the combination with means for 45 traversing two shuttles through two warp-sheds at each pick of the loom, a rotatable magazine containing a reserve supply of weft or filling in the form of concentrically-arranged weft-holders, means for rotating said magazine and a restraining device preventing periodically said rotation, said restraining device being made operative when two of the said weft-holders engage it, and inoperative on either one or both of said weft-holders being removed from said engagement, 55 combined with drivers adapted to transfer said weft-holders from the magazine to the shuttles in play, means for controlling the time of operation thereof, said means consisting of an electric circuit connected with said supplying mechanism and made inoperative and operative, respectively, by the presence or absence of weft or filling in the 60 shuttles in play.

11. In a weft or filling supplying mechanism, the combination with means for travers-

ing two shuttles through two warp-sheds at each pick of the loom, a rotatable feeder or magazine containing a reserve supply of weft or filling in the form of concentrically-arranged weft-holders adapted to be driven or pushed into shuttles, means for always maintaining two of said weft-holders at the delivery-point adjacent to the said shuttles, 70 means for driving or pushing during the same pick of the loom, either or both of the said weft-holders into the shuttles in play, substantially as set forth.

12. In a weft or filling supplying mechanism, the combination with means for traversing two shuttles through two warp-sheds at each pick of the loom, a rotatable feeder or magazine containing a reserve supply of weft or filling in the form of concentrically-arranged weft-holders adapted to be driven or pushed into shuttles, means for always maintaining two of said weft-holders at the delivery-point adjacent to the said shuttles, 80 means for driving or pushing during the same pick of the loom, either or both of the said weft-holders into the shuttles in play, the time of operation thereof being controlled by the presence or substantial absence of weft or filling in the shuttles in play.

95 13. In a weft or filling supplying mechanism, the combination with means for traversing two shuttles through two warp-sheds at each pick of the loom, a rotatable feeder or magazine containing a reserve supply of weft or filling in the form of concentrically-arranged weft-holders adapted to be driven or pushed into shuttles, means for always maintaining two of said weft-holders at the delivery-point adjacent to the said shuttles, 100 means for driving or pushing, during the same pick of the loom, either or both of the said weft-holders into the shuttles in play, and means for controlling the time of operation of said supplying mechanism, said means consisting of an electric circuit connected with the same and made inoperative by the presence and operative by the substantial absence of weft or filling in the shuttles in play.

110 14. In a double-shuttle loom, having means for picking two shuttles through two warp-sheds, a weft or filling replenishing mechanism comprising a rotatably-mounted magazine, having means for carrying bobbins or weft-holders arranged concentrically on the 115 magazine, means tending to rotate said magazine, a restraining device that periodically restrains said rotation, means for rendering said restraining device inoperative to permit the magazine to rotate to the extent of the 120 space occupied by one bobbin or weft-holder when a weft-holder is supplied to the upper shuttle, and inoperative to the extent of the space occupied in the magazine by two bobbins or weft-holders when a weft-holder is 125 supplied to either the lower or both the lower and the upper shuttles, the times of operation thereof being controlled by the presence or 130 substantial absence of weft or filling in the 135

shuttles in play, and means for transferring the weft-holders from the magazine to the respective shuttles.

15. In a double-shuttle loom having means for picking two shuttles through two warp-sheds, a weft or filling replenishing mechanism comprising a rotatably-mounted magazine having means for carrying concentrically-arranged bobbins or weft-holders, means tending to rotate said magazine and a restraining device that periodically restrains said rotation, means for rendering said restraining device inoperative to permit the magazine to rotate to the extent of the space occupied in the magazine by one bobbin or weft-holder when a weft-holder is supplied to the upper shuttle, and inoperative to the extent of the space occupied in the magazine by two bobbins or weft-holders when a weft-holder is supplied to either the lower or both the lower and the upper shuttles, and means for controlling the times of operation thereof said means consisting of an electric circuit connected with said replenishing mechanism, same being made inoperative and operative, respectively, by the presence or substantial absence of weft or filling in the shuttle in play.

16. In a loom having two shuttles traversing the two warp-sheds, and two superposed shuttle-boxes, means for picking the said shuttles, a weft or filling mechanism comprising a magazine or holder for a reserve supply of weft or filling, said magazine being rotatably mounted and having an axial boss, a single head or end, arms on said head and extending therefrom, and concentrically-arranged clips for supporting weft-holders therein, means for effecting, when required, on the same pick of the loom, the transfer of either one or two weft-holders from said magazine to either or both of the shuttles in play, and exhaustion-indicating devices controlling the times of operation of said transferring mechanism.

45 17. In a loom having two shuttles traversing the two warp-sheds, and two superposed shuttle-boxes, means for picking the said shuttles, a weft or filling replenishing mechanism comprising a magazine or holder for a reserve supply of weft or filling, said magazine being rotatably mounted and having an axial boss, a single head or end, arms on said head and extending therefrom, and concentrically-arranged clips for supporting weft-holders therein, means for effecting, when required, on the same pick of the loom, the transfer of either one or two weft-holders from said magazine to either or both of the shuttles in play and electromechanical means for controlling the times of operation of said mechanism.

60 18. In a double-shuttle loom, a weft-replenishing device comprising a magazine rotatably mounted and having means for securing in it the weft-holders arranged concentrically with the center of rotation, the axis of said magazine being substantially on a level with a point midway between the two superposed

shuttle-boxes, and the space between adjacent bobbins in the magazine being substantially equal to that between the shuttles in the respective boxes, means tending constantly to rotate said magazine, a detent device to prevent rotation of the magazine, means for driving weft-holders from the magazine into the shuttles at the delivery-point, and exhaustion-indicating devices controlled by the presence or absence of weft or filling in the respective shuttles in play, for setting in action said driving mechanism.

19. In a weft-supplying mechanism for looms, the combination with the rotatably-mounted magazine, provided with concentrically-arranged means for securing weft-holders therein, means for rotating said magazine, and means for arresting the rotation of said magazine, of two drivers extending into said magazine and adapted for driving out laterally two contiguous weft-holders therefrom, means for operating said drivers independently, and exhaustion-indicating devices controlled by the presence or absence of weft or filling in the respective shuttles for setting in operation said supplying mechanism.

20. In a weft-replenishing mechanism for looms, the combination with the rotatably-mounted weft-holding magazine, means tending to rotate said magazine, and means for driving from said magazine two contiguous weft-holders, of a compound detent for arresting the rotation of the magazine, said device comprising the two pivotally-mounted detents *u*, *u'* so spaced as to bear on contiguous or next adjacent weft-holders in the magazine, the link connecting said detents at opposite sides of their pivotal points, and means to prevent an excess of movement of said detents.

21. In a double-shuttle loom having two superposed shuttle-boxes, a weft-supplying mechanism having a rotatably-mounted magazine comprising a sleeve-like boss *j*, a head *i*, a ring *l*, securing devices on said head and ring for a concentrically-arranged series of weft-holders, and bars *k*, connecting said head and ring, in combination with means tending to rotate said magazine, a compound, vibratable detent device within said magazine and tending to prevent its rotation, and means for transferring either or both of the weft-holders at the delivery-point into their respective shuttles.

22. In a loom, the combination with a device for supporting the weft, said device comprising a spindle provided with a spring-indicator, and a butt-cop or weft-holder adapted to fit on said spindle, of a shuttle to receive said weft-supporter and provided with means for grasping and holding the same firmly but detachably in place therein.

23. In a loom, the combination with a device for supporting weft or filling, said device comprising a spindle provided with a spring-indicator, and a weft-holder adapted to fit on said spindle, said weft-holder having in it a slot to receive said indicating device, of a shuttle

adapted to receive said weft-supporter, and provided with means for grasping and holding the same firmly but detachably in place therein.

5 24. The combination with a laterally-compressible metal spindle provided with a slotted head, a metal contact-piece bridging said slot, and a spring-indicator extending through said slot under said contact-piece, of a weft-holder 10 adapted to slip over said spindle and to be held thereon frictionally, said weft-holder having in it a slot to receive the said indicator.

25. In a weft-supplying mechanism for looms having means for picking two shuttles 15 through two warp-sheds, the combination with the rotatively-mounted weft-holding magazine, means for driving, as required, from said magazine, on the same pick of the loom, either one weft-holder or two contiguous weft-hold-

ers, into the respective shuttles, of a device 20 for arresting the rotation of the magazine, said device comprising two stops, so spaced as to bear on contiguous or next adjacent weft-holders in the magazine, and an exhaustion-indicating device made inoperative and 25 operative, respectively, by the presence or substantial absence of weft or filling in the shuttles in play, which control the times of operation of said mechanism.

In witness whereof we have hereunto signed 30 our names, this 9th day of April, 1900, in the presence of two subscribing witnesses.
